CLAIM

I claim the ornamental design for a balustrade system, as shown and described.

DESCRIPTION

FIG. 1 is a top perspective view of a balustrade system according to the present invention; and,
FIG. 2 is a top perspective view of a balustrade system according to the present invention as in FIG. 1 but showing additional environmental structure.

Features of the balustrade system illustrated in broken lines in the Figures depict environmental structure shown for illustrative purposes only and form no part of the claimed design. The dot-dash-dot break lines depict the boundaries of the Claim. The area between the dot-dash-dot break lines forms no part of the claimed design. Portions of the balustrade system that may be visible between the dot-dash-dot break lines have been removed for clarity.
